W. R. COLLINS

ADJUSTABLE GOLF CLUB

Filed Aug. 5, 1927.

Patented Oct. 4, 1927.

1,644,177

UNITED STATES PATENT OFFICE.

WILLIAM R. COLLINS, OF DETROIT, MICHIGAN.

ADJUSTABLE GOLF CLUB.

Application filed August 5, 1927. Serial No. 210,820.

My invention relates to a new and useful improvement in golf clubs shown in the accompanying drawings and more particularly described in the following specification and 5 claims.

It is well-known that the principal difference between many of the clubs used in playing golf,—such as the putter, midiron, niblick, mashie, and loftier,—is the angle to 10 which the striking surface of the head of the club is presented to the ball when struck thereby.

Therefore the primary object of the present invention is to provide in a single club 15 means whereby the angle of the head or blade may be readily and easily adjusted to take the place of any one of several clubs usually employed.

I am aware that adjustable golf clubs have 20 been constructed heretofore, but the same are more or less objectionable, either on account of the difficulty in making the required adjustment due to the necessity of carrying certain tools whereby the desired adjustment 25 may be made, or that the head is not securely held in its adjusted position, or for other well-known reasons.

The purpose of the present invention is to 30 provide a simple and inexpensive club, which may be easily adjusted without the use of tools—with no parts likely to become detached or lost—and in which the desired disposition of the head of the club may be readily and accurately determined by reference 35 to a graduated scale indicating the several angles corresponding with the usual angle of the heads on the clubs numerated,—or whereby an intermediate adjustment may be made which the golfer finds through practice improves his game.

A further object of the invention is to provide means whereby the head may be adjusted upon a supporting stub shaft extending from the club shaft, by merely rotating the 45 head in a counter-clockwise direction upon the shaft,—the construction being such that the head is automatically and securely held at any desired degree as rotated:—in contradistinction to the necessity of first manually withdrawing the head from a locking to a released position,—then manually adjusting the head while the parts are in released relation, and under tension of a relatively powerful spring,—the head being then shifted back 50 to locked relation upon the stub shaft of the club.

A further object of the invention is to provide a visible indicator whereby the degree of adjustment may be made to correspond with the customary angles of the various 60 clubs previously enumerated.

With the foregoing and other objects in view which will appear as the description proceeds, the invention further resides in the details of construction hereinafter described 65 and claimed, it being understood that changes may be made in the precise embodiment if the invention herein disclosed without departing from the spirit of the same.

In the drawings accompanying this specification:

Figure 1 is an elevation of the lower end of a club embodying my invention.

Figure 2 is a similar view of the head partly broken away and in section, showing details of construction.

Figure 3 is an end elevation of the head showing the graduated scale and co-operating index provided on the end of the stub shaft.

Figure 4 is a sectional elevation of a modification in the construction of the club.

Figure 5 is a detail view of a removable graduated disc co-ordinating with the index on the end of the stub shaft.

Figure 6 is a cross-sectional view taken on or about line 6—6 of Figure 2.

Figure 7 is a cross-sectional view taken on or about line 7—7 of Figure 4.

Referring now to the letters of reference 90 placed upon the drawings:

A denotes the shaft of a club fitted at its lower end with a tapered shank B to which is rigidly secured a stub shaft C extending at an angle to the tapered shank.

D is an adjustable head loosely sleeved upon the stub shaft C, counterbored at one end to accommodate a spring E, bearing against a shoulder d formed in the head by the counterbore.

F indicates a washer sleeved upon the stub shaft provided with an inwardly extending tongue f projecting into a peripheral groove C^a formed in the stub shaft to secure the washer against rotation.

G indicates an adjustable nut, tapped to receive the threaded end of the stub shaft and bearing against the washer, by adjusting which the tension of the spring E may be regulated.

The head D at its outer end is provided with a second counterbore to receive an an-

nular gasket H upon which is placed a washer I, formed of fiber or other suitable material on which is printed or otherwise impressed a series of graduations I^a, designed 5 to co-ordinate with an index finger or pointer C^b, formed on the outer end of the stub shaft,—that the head D may be adjusted to any desired angle upon the shaft, predetermined through reference to the respective 10 graduations upon the washer I.

J denotes a glass lens covering the graduated washer I and secured against displacement in the head by a locking ring K or other suitable means.

15 The opposite end of the head D is formed with a plurality of ratchet teeth D^a adapted to interlock with like teeth B^a formed on the lower end of the tapered shank B.

It will now be apparent that upon grasping 20 the shank B in one hand, the head D may be rotatably adjusted by the other hand in a counter-clockwise direction so that the striking surface of the head may be adjusted with reference to the shaft to any desired 25 angle, the graduations indicated on the washer I corresponding with the angles of the striking surfaces of the various clubs previously referred to.

It will also be apparent that any intermediate 30 adjustment may be secured by rotating the head to either a greater or lesser extent.

In the modification shown in Figures 4 and 7, a sleeve L is formed with ratchet teeth 35 L^a, interlocking with the ratchet teeth B^a on the tapered shank B, the sleeve L being secured to the head by a pin L^b or other suitable means.

The head shown in Figures 1 and 2 is 40 preferably constructed of high-grade tool steel in order that the ratchet teeth may withstand wear.

In the modification shown in Figures 4 and 7, a somewhat cheaper club is provided 45 in which the sleeve L only is formed of high-grade tool steel, that the ratchet teeth may resist wear, while the head in this case may be of relatively lower grade material.

It will be noted that in adjusting the club 50 to meet the requirements of the golfer, it is not necessary to pull the head out of interlocking relation with the shank so that the teeth on the end of the former may be released from engagement with the teeth on 55 the shank,—and when so released to manually maintain it in said released condition against the action of the spring while adjusting the head to the position desired.

As the spring employed is necessarily one 60 of great tension, this is a difficult thing to accomplish,—and especially is this true where the club is used by a woman or child.

By the use of my invention, the golfer has 65 only to hold the shaft in one hand while rotating the head with the other hand in

a counter-clockwise direction,—the ratchet teeth thus automatically ride into and out of engagement as the head is rotated. The club may thus be locked at any degree of adjustment, the operation being exceedingly 70 simple and can be accomplished by anyone with little effort.

By providing the end of the stub shaft with an index finger collaborating with the 75 graduations of the washer, an adjustment of the head conforming to the striking surface of several clubs may be readily pre-determined. This adjustment however is capable of a further finer adjustment to suit the ideas and requirements of the golfer.

It will be obvious that in constructing a club of this description for the use of left-hand golfers, the interlocking ratchet teeth will be inclined in an opposite direction to that disclosed in the drawings.

Having thus described my invention what I claim is:

1. A golf club comprising a shaft; a shank secured thereto having a heel formed with radial ratchet-faced teeth; a stub shaft secured to the heel and projecting at an angle therefrom; an adjustable head sleeved upon the stub shaft carrying ratchet teeth adapted to interlock with the ratchet teeth on the heel of the shank; a coiled spring sleeved upon the stub shaft adapted to bear upon the adjustable head; and a nut screwed upon the end of the stub shaft adapted to adjust the tension of the spring to force the ratchet teeth carried by the adjustable head into 95 yieldable interlocking relation with the ratchet teeth on the heel of the shaft.

2. A golf club comprising a shaft; a shank secured thereto; a stub shaft secured to the heel of the shank projecting at an angle 100 therefrom and threaded to receive a nut; an adjustable head loosely sleeved upon the stub shaft counterbored at its forward end to receive a spring; a coiled spring sleeved upon the stub shaft adapted to bear upon a shoulder in the adjustable head formed by the counterbore; and a nut tapped to receive the threaded end of the stub shaft adapted to adjust the tension of the spring, the abutting ends of the heel and shank being 110 respectively formed with interlocking ratchet-faced teeth, whereby upon manually rotating the head upon the stub shaft, the head may be automatically, and alternately released and locked to the shank, until a pre-determined adjustment is effected.

3. A golf club comprising a shaft; a shank secured thereto; a stub shaft secured to the heel of the shank and projecting at an angle 115 therefrom with its forward end threaded to receive a nut; an adjustable head loosely sleeved upon the stub shaft counterbored at its forward end to receive a spring; a coiled spring sleeved upon the stub shaft adapted to bear upon a shoulder in the adjustable 120

head formed by the counterbore; a washer sleeved upon the stub shaft adjacent to the spring; and a nut tapped to receive the threaded end of the stub shaft, adapted to 5 adjust the tension of the spring, the abutting ends of the adjustable head and heel of the shank being respectively formed with interlocking ratchet-faced teeth, whereby upon manually rotating the head upon the stub 10 shaft, the head may be automatically and alternately released, and locked to the shank, until a pre-determined adjustment is effected.

4. A golf club comprising a shaft; a shank 15 secured thereto; a stub shaft secured to the heel of the shank and projecting at an angle therefrom with its forward end threaded to receive a nut; an adjustable head loosely sleeved upon the stub shaft; a coiled spring 20 sleeved upon the stub shaft adapted to bear upon a shoulder in the adjustable head; a washer sleeved upon the stub shaft adjacent the spring, having a tongue extending into a longitudinal groove formed in the stub 25 shaft; and a nut tapped to receive the threaded end of the stub shaft adapted to adjust the tension of the spring, the abutting ends of the adjustable head and heel of the shank being respectively formed with interlocking 30 ratchet-faced teeth, whereby upon manually rotating the head upon the stub shaft the head may be automatically and alternately released and locked to the shank until a pre-determined adjustment of the head is effected.

5. A golf club comprising a shaft; a shank secured thereto having a heel formed with radial ratchet-faced teeth; a stub shaft secured to and projecting at an angle from 40 the heel of the shank carrying an index pointer at its outer end; an adjustable head sleeved upon the stub shaft carrying graduations at its forward end coordinating with the index pointer on the stub shaft, said

adjustable head having at its opposite end 45 ratchet teeth adapted to interlock with the ratchet teeth on the heel of the shank; a coiled spring sleeved upon the stub shaft adapted to bear upon a shoulder in the adjustable head; and a nut screwed upon the 50 end of the stub shaft adapted to adjust the tension of the spring, whereby the ratchet teeth carried by the adjustable head may be forced automatically into yieldable interlocking relation with the ratchet teeth on the 55 heel of the shank.

6. A golf club comprising a shaft; a shank secured thereto having a heel formed with radial ratchet-faced teeth; a stub shaft secured to and projecting at an angle from 60 the heel of the shank having an index pointer at its outer end; an adjustable head sleeved upon the stub shaft having ratchet teeth at one end adapted to interlock with the ratchet teeth on the heel of the shank; a coiled 65 spring sleeved upon the stub shaft adapted to bear upon a shoulder in the adjustable head; a washer sleeved upon the stub shaft adjacent the spring having a tongue extending into a longitudinal groove in the stub 70 shaft; a nut screwed upon the end of the stub shaft adapted to bear upon the washer to adjust the tension of the spring, whereby the ratchet teeth carried by the adjustable head may be forced automatically into yieldable 75 interlocking relation with the ratchet teeth on the heel of the shank; a graduated washer secured in the adjustable head at the end of the stub shaft, whereby its graduations may co-ordinate with the index pointer at the end of the stub shaft; a glass lens covering the graduated washer; and means for securing the glass lens in the adjustable head.

In testimony whereof, I sign this specification.

WILLIAM R. COLLINS.
